UNITED STATES PATENT OFFICE.

JULES REGOUT, JR., OF MAASTRICHT, NETHERLANDS.

MACHINE FOR RAISING NAP ON FABRICS.

1,384,920.

Specification of Letters Patent. Patented July 19, 1921.

Application filed July 23, 1919. Serial No. 312,867.

To all whom it may concern:

Be it known that I, JULES REGOUT, Jr., manufacturer, a subject of the Queen of the Netherlands, residing at Maastricht, No. 18 5 Kleine Lovierstraat, in the Kingdom of the Netherlands, have invented certain new and useful Improvements in Machines for Raising Nap on Fabrics; and I do hereby declare the following to be a full, clear, and exact 10 description of the invention, such as will enable others skilled in the art to which it appertains to make and use the same.

This invention relates to improvements in machines for raising nap on fabrics of the 15 character in which the raising action may be effected simultaneously in the direction of the warp of the fabric as well as transversely to the same, such as disclosed for example in my Letters Patent of the United 20 States No. 1217129 of February 20, 1917.

The primary object of the present invention is to provide a machine of this character in which the raising rollers and the driving means for the same are mounted in 25 a fixed frame, while the fabric is being guided through a traveling carriage which is movable to and fro on the fixed frame transversely to the traverse of the fabric.

Another object of the invention is to provide in said machine means for deriving the reciprocating motion of the traveling carriage from the driving mechanism for the raising rollers.

A still further object of the invention is to 35 provide the said machine with means for converting the reciprocating motion of the traveling carriage into a constant rotary motion which in turn is made use of for driving the feeding rollers of the fabric.

40 With these and other ends in view my invention consists in the arrangement, construction and combination of parts to be herein described and particularly pointed out in the appended claims.

45 In the drawings:

Figure 1 is a front view, partly in section, of the machine constructed in accordance with the present invention.

Fig. 2 is an end view of the same, partly 50 in section.

Figs. 3 and 4 are detail views of parts of the gearing.

Figs. 5, 6, 7 and 8 are views of further details of the gearing.

55 Referring now to the drawings, in which similar numerals of reference indicate corre-

sponding parts, 5 designates a fixed frame in which are mounted the raising rollers 6 and 7. The raising rollers 6 are arranged with their axes in the direction of the traverse of the fabric 8, *i. e.* in the direction of the warp, and the raising rollers 7 transversely of the traverse of the fabric, *i. e.* in the direction of the weft. The rollers 6 are preferably eight in number (comprising two groups of four rollers) and the rollers 7 are two in number. In the groups of the four rollers 6 the pairs of rollers lying on opposite sides of the longitudinal axis of the machine turn outward, while the rollers 7 turn in a direction opposite to the direction in which the fabric 8 passes through the machine. The mechanism for rotating the raising rollers is driven from a main pulley 9, adjacent to which is mounted an idle pulley 10. The pulley 9 is driven from any suitable source of power. Both pulleys 9 and 10 are mounted on a shaft 11 from which the rotation is transmitted through belts to shafts 12, 13 and 14 which are suitably 80 mounted in the frame 5 in any well-known manner. The shafts 12, 13 and 14 are in driving connection with the raising rollers 6 and 7 by means of belts, toothed and bevel-wheels which cause rotation of the raising 85 rollers in the desired direction. As in my Patent No. 1217129 before referred to, the transverse rollers 7 are vertically adjustable with respect to the fabric 8, in order to obtain an increased raising effect either in the 90 direction of the warp or in the direction of the weft of the fabric. To enable this, the rotation of the shaft 14 is transmitted to vertical shafts 15 by means of bevel-gears 16. The upper ends of the shafts 15 are in 95 turn in driving connection with the shafts of the rollers 7 by means of bevel-gears 17. Each shaft 15 consists of two parts which are longitudinally slidable one within the other and which are journaled in bearings 100 18 and 19, respectively. The bearings 19 are mounted on brackets 20 which support the shafts of the raising rollers 7 and which are vertically adjustable in guides formed on the frame 5. The lower ends of the 105 brackets 20 are engaged by threaded spindles 21 which are guided in internally threaded housings 22 which are fastened to the frame 5. Below the housings 22 the spindles 21 are provided with worm wheels 23 which are 110 in engagement with worms 24 fixed on a shaft 25. This shaft is journaled in the

frame 5 and is provided at its free end with a hand wheel 26 by means of which the shaft may be rotated in one direction or the other. It is evident, that by rotating the 5 shaft 25, the spindles 21 will be screwed upward or downward, thereby elevating or lowering the brackets 20 and along with them the upper parts of the shafts 15 and the raising rollers 7. The rollers 7 are thus 10 brought into contact more or less intensive with the fabric 8 or moved into inoperative position, *i. e.* entirely out of contact with the fabric.

Loosely mounted on shaft 12 near each 15 of its ends is a sprocket-wheel 27 which can be coupled with shaft 12 by the aid of a suitable clutch controlled by a lever (not shown). The sprocket-wheel 27 is connected by an endless chain 28 to another sprocket- 20 wheel 29 which is fastened to one end of a shaft 30 journaled in a bearing 31 (Fig. 3) supported by the upper part of the frame 5. The other end of shaft 30 is provided with a sprocket-wheel 32 to which is adapted a 25 chain 33 which passes around a sprocket-wheel 34 the shaft of which is mounted in a bearing 35 (Fig. 3) supported by the frame 5. The chain 33 is provided with a stub shaft 36. This shaft projects into an 30 oval slot 37 which is formed in a beam 38 of the traveling carriage 39 which guides the fabric 8. The stub shaft 36 is movable up and down in the slot 37 and when running with the chain 33 imparts a to and fro 35 motion to the carriage 39. The carriage 39 is provided with grooved wheels 40 by means of which it travels on rails 41 which are supported by the frame 5.

Feeding rollers 42 and idler rollers 43 are 40 mounted in the frame of the carriage 39 and serve to guide the fabric 8 through the machine in the direction of the axes of the raising rollers 6 and transversely to the rollers 7.

The reciprocating motion of the carriage 45 39 is converted into a constant rotary motion which is made use of for propelling the guiding rollers 42. To this end, the carriage 39 is provided with arms 44 in which is 50 rotatably mounted a shaft 45 (Fig. 4). The shaft 45 carries on its intermediate part a spur-wheel 46 which is in engagement with a rack-bar 47 which is fastened to a bracket 48 of the frame 5 (Fig. 1). On both sides of the spur-wheel 46, the shaft 45 has loosely 55 mounted thereon bevel wheels 49. Fastened rigidly to and concentrically with the bevel-wheels 49 are ratchet-wheels 54 which have oppositely directed teeth (see Figs. 4, 5 and 7). These ratchet-wheels 54 are engaged by 60 pawls 55 which are swingingly mounted on pivots 56 carried by segments 57 which are fastened to the opposite side faces of the spur-wheel 46 or the shaft 45, respectively. The pawl 55, shown in Fig. 6, coöperates 65 with the ratchet-wheel 54, shown in Fig. 5,

and the pawl 55, shown in Fig. 8, coöperates with the ratchet-wheel 54, shown in Fig. 7. The pawls are held against stops 58 of the segment 57 by means of springs 59. The stops have angular faces 60, 61. The pawls lie 70 against the faces 60 when in operation, *i. e.* when engaging the teeth of the ratchet-wheels 54 to rotate the same. The faces 61 limit the swinging motion of the pawls, when the pawls glide in a reverse direction 75 over the teeth of the ratchet-wheels 54. It is evident that, when the spur-wheel 46 is intermittently rotated by the reciprocating movement of the carriage, the bevel-wheels 49 are alternately rotated in opposite directions through the medium of the described ratchet- and pawl-mechanisms. The construction of these mechanisms, which forms no part of this invention, may also be of any other well-known kind.

Both bevel-wheels 49 are in engagement with a common bevel-wheel 50 to which a constant rotation in one direction is imparted through the alternate rotating of the wheels 49 in opposite directions. The bevel-wheel 50 is fastened to one end of a shaft 51 which is rotatably mounted in the frame of the carriage 39 and which, on its other end, carries a sprocket-wheel 52 around which passes a chain 53 (Fig. 1) which transmits 95 the necessary rotation to the guiding-rollers 42 for the fabric 8.

When the raising rollers 6 and 7, driven from the pulley 9, are rotating and the sprocket-wheel 27 is coupled with the shaft 12, so that the traveling carriage 39 is given its reciprocating motion through the mechanism described, each point of the fabric moves on a regular zigzag line across the raising rollers, whereby a highly efficient 105 raising action is attained. By not coupling the sprocket-wheel 27 with the shaft 12, the carriage 39 can be held in non-operative position, in which case each point of the fabric will travel on a straight line across 110 the raising rollers.

In order to give the fabric the necessary forward motion in the last-mentioned case, one end of the shaft carrying the main pulley 9 is provided with a pulley 62, and another pulley 63 is fastened to the shaft of one of the feeding-rollers 42. These pulleys 62 and 63 can be brought into driving connection by means of a half-crossed belt 64. The belt 64 is normally thrown off and is only put on when the sprocket-wheel 27 is uncoupled from the shaft 12 and it is desired to move the fabric on a straight line as stated.

All raising rollers are removably mounted 125 in their bearings or on their shafts, respectively, so that they can easily be exchanged without interfering with the operation of the machine. In order to avoid undue friction, most bearings are constructed as ball- 130

or roller-bearings. The belts and pulleys of the driving mechanism for the raising rollers are arranged in such a manner that all parts are easily accessible and that the 5 belts may be conveniently thrown off.

By mounting the raising rollers and the driving means for the same in a fixed frame or base instead of in the traveling carriage such as is the case for example with the 10 machine of my afore-mentioned prior Patent No. 1217129, the traveling carriage which must be moved to and fro, it rendered much simpler and of much less weight. Therefore, the power necessary for executing the 15 movement of the carriage is also much reduced. Besides, the entire machine can be driven by a single belt from any suitable source of power (vapor, electricity, gas). The traveling carriage needs no special 20 driving means, its reciprocating movement being derived from the propelling mechanism for the raising rollers, and the reciprocating motion being in turn utilized for causing the rotation of the fabric guiding 25 rollers.

It is obvious that various modifications may be made in the construction shown and above particularly described within the principle and scope of my invention.

30 What I claim as new and desire to secure by Letters Patent, is:—

1. A machine for raising nap on fabrics, comprising a fixed frame, a traveling carriage movable to and fro on said frame, a 35 plurality of raising rollers and driving means for the same mounted in said frame, some of the rollers being adjustable in height, rollers for guiding the fabric through the machine, said rollers being 40 mounted on the traveling carriage, means for deriving the reciprocating motion of the carriage from the driving mechanism for the raising rollers, and means for converting the reciprocating motion of the carriage 45 into a rotary motion for rotating the guiding rollers for the fabric.

2. A machine for raising nap on fabrics, comprising a fixed frame, a traveling carriage movable to and fro on said frame, a 50 plurality of raising rollers mounted in said frame, driving mechanism for rotating the raising rollers also mounted in said frame, chain-drives between one of the shafts of the said driving mechanism and shafts 55 mounted in the upper part of the frame, the latter shafts being connected with idle shafts by further chain-drives, the chains of the latter carrying stub shafts engaging and movable in oblong slots of the frame

60 of the carriage and imparting a reciprocating motion to the carriage transversely to the traverse of the fabric, guiding rollers for the fabric on the carriage, and means for converting the reciprocating motion of 65 the carriage into a constant rotary motion

for rotating the guiding rollers for the fabric.

3. A machine for raising nap on fabrics, comprising a fixed frame, a traveling carriage movable on the frame, a plurality of 70 raising rollers mounted in the frame, propelling means for the raising rollers likewise mounted in the fixed frame, chain-drives between the said driving means and the traveling carriage for imparting a to and fro motion to the carriage, rollers on the carriage for guiding the fabric across the raising rollers, shafts on the carriage carrying toothed spur-wheels, said spur-wheels being in engagement with and movable over 80 horizontal rack-bars fastened to the fixed frame, bevel-wheels loosely mounted on the said shafts on both sides of the spur-wheels and alternately rotated by the latter in opposite directions, said bevel-wheels engaging 85 with and giving constant rotation in one direction to bevel-wheels which are mounted on shafts lying at right angles to the shafts which carry the spur-wheels and the first-mentioned bevel-wheels, and being in driving 90 connection with the guiding rollers for the fabric.

4. A machine for raising nap on fabrics, comprising a fixed frame, a traveling carriage movable on the frame, a plurality of 95 raising rollers mounted in the frame, driving means for the raising rollers likewise mounted on the fixed frame, chain-drives between the said driving means and the traveling carriage for imparting a to and fro motion to the carriage, rollers on the carriage for guiding the fabric, shafts on the carriage carrying toothed spur-wheels which are in engagement with and movable over 100 horizontal rack-bars fastened to the fixed frame, bevel-wheels loosely mounted on the said shafts on both sides of the spur-wheels, ratchet and pawl mechanisms between the spur-wheels and the bevel-wheels, said ratchet and pawl mechanisms operating 105 in opposite directions and alternately rotating the bevel-wheels in opposite directions, said bevel-wheels engaging with and given constant rotation in one direction to bevel-wheels which are mounted on shafts lying 110 at right angles to the first-mentioned shafts and being in driving connection with the fabric guiding rollers for imparting a constant rotary motion to said rollers.

5. A machine for raising nap on fabrics, 115 comprising a fixed frame, a traveling carriage movable to and fro on the frame, a plurality of raising rollers and propelling means for the same mounted on the frame, some of the rollers being adjustable in 120 height, these rollers being journaled in bearings mounted on brackets which are vertically guided on the fixed frame, threaded spindles operating on the brackets, said spindles being guided in internally threaded 130

- 10
- housings supported by the fixed frame and being in engagement with a horizontal shaft by means of worm gears, a hand-wheel on the horizontal shaft to rotate the same and thereby raise or lower the threaded spindles with the brackets supporting the said raising rollers, guiding rollers for the fabric mounted on the traveling carriage, means
- 5

for deriving the reciprocating motion of the carriage and the rotary motion of the guiding rollers from the driving means for the raising rollers mounted in the fixed frame.

In testimony whereof I have signed my name to this specification.

JULES REGOUT, Jr.
